Des. 226,305
Patented Feb. 13, 1973

226,305

PACKAGING TRAY

Lawrence T. Wilkes, Lancaster, Ohio, assignor to Anchor
Hocking Corporation, Lancaster, Ohio

Filed Apr. 7, 1971, Ser. No. 132,250

Term of patent 14 years

Int. Cl. D9—03

U.S. Cl. D9—188

FIG. 1 is a top plan view of a packaging tray showing my new design;

FIG. 2 is a side elevational view thereof, the other side being the same;

FIG. 3 is an end elevational view thereof, the other end being the same;

FIG. 4 is an enlarged fragmentary top plan view thereof;

FIG. 5 is an enlarged fragmentary bottom plan thereof;

FIG. 6 is a further enlarged vertical section taken along lines 6-6 in FIG. 4; and

FIG. 7 is a further enlarged vertical section taken along lines 7-7 in FIG. 4.

I claim:

The ornamental design for a packaging tray, substantially as shown and described.
